SHOE INSEAM SEWING MACHINE

Otto R. Haas, Beverly, Mass., assignor to United
Shoe Machinery Corporation, Flemington, N. J.,
a corporation of New Jersey

Application June 6, 1947, Serial No. 752,868

3 Claims. (Cl. 112—50)

1

The present invention relates to shoe inseam sewing machines and particularly to novel means for determining the correct position of the needle in its clamping device and the proper relationship between the needle and the channel guide for most effective sewing operations.

In the machine of United States Letters Patent No. 1,003,175, granted September 12, 1911, in the name of Andrew Eppler, there is provided a gage for determining the correct position of the channel guide to insure positioning of a shoe during sewing operations. With the channel guide correctly positioned the sewing devices of the machine may be regulated in a number of different ways to enable successful sewing operations to be performed on a particular type of work. In adjusting the sewing devices it is common practice to change the position of the more readily accessible devices among which are the needle and the looper before attempting to adjust the more inaccessible devices. Accordingly, the relationship between the needle and the channel guide may be changed with an apparently satisfactory result for the particular type of work if special compensating adjustments are made in others of the stitch forming devices and when another type or quality of work is operated upon great difficulty will be encountered in regulating the sewing devices for effective results. Thus, if the needle, after its work penetrating stroke, does not retract sufficiently to form a properly tensioned stitch it is possible thereafter to tighten the stitch during the stitch setting operation of the machine with the requisite tension if the stroke of the take-up is increased. Inasmuch as the stitch tightening operation of the needle is determined fundamentally by its relationship with the channel guide, an object of the present invention is to provide means for insuring a standard predetermined stitch tightening action during the retracting movement of the needle without special compensating adjustments in other stitch forming devices. Another object of the invention is to enable adjustments of the channel guide and needle of a shoe inseam sewing machine to be made in such relationship that satisfactory sewing results may be obtained for any type or quality of work within the range intended to be covered by the machine.

To the ends above noted the present invention includes an inseam sewing machine having a curved hook needle, a segment in which the needle is adjustably clamped, and mechanism for actuating the segment to move the needle

2

through a constant arcuate path toward and from the work in which a movable gage is mounted on the machine frame and arranged to be shifted by the operator toward and from the needle path, into and out of gaging position with the needle so that the needle may be clamped within the needle segment at the correct location. This feature of the invention also contemplates the provision of gage means cooperating with the channel guide in a manner similar to that of the Eppler patent above identified. In the illustrated form of this feature the machine is provided with a pair of pivoted arms having shoulders for contacting the lip of the channel guide and the hook of the needle and arranged for separate swinging movements toward and from gaging positions.

These and other features of the invention consist in certain devices, combinations and arrangements of parts hereinafter described and claimed, the advantages of which will be apparent from the following description taken in connection with the accompanying drawings, in which:

Fig. 1 is a view in right side elevation of a shoe inseam sewing machine embodying the features of the present invention;

Fig. 2 is a detail plan view on an enlarged scale of the needle and channel guide gage arms of the machine of Fig. 1 illustrated in their gaging positions; and

Fig. 3 is a detail view in elevation of the same arms.

The machine illustrated in the drawing is a curved hook needle chain stitch welt shoe sewing machine and is similar in construction and mode of operation to that of the Eppler patent above noted and of Patent No. 1,108,560, granted August 25, 1914, in the name of the same inventor.

Referring to the drawings the curved hook needle is illustrated at 2, a curved awl at 4, a needle looper at 6, a channel guide at 8, a welt guide at 10 and a back rest at 12. The machine is also provided with a channel guide gage 14 in the form of a swinging arm mounted on a main frame 15 of the machine in a manner similar to that of Patent 1,003,175.

To adjust the channel guide 8 as in the machine of the patent it is necessary to free it from its actuating mechanism by loosening a clamp bolt indicated at 16 in Fig. 1, as more fully described in the Eppler patent. The channel guide is then moved transversely of the direction of feed to bring its work engaging end or lip into contact with a shoulder on the gage 14 while the gage is held in raised position. After

such adjustment of the channel guide it has been found that effective sewing operations still may be performed only by further and more complicated adjustment in the stitch forming devices of the machine particularly the needle, looper and take-up indicated at 18. These adjustments, if expertly performed, provide satisfactory sewing operations on a particular type of work, but with changes in type or quality of the work further adjustments are required.

To insure uniformly satisfactory sewing operations with different types of work throughout the operating range of the machine without the necessity of making further adjustments when the type or quality of work is changed, according to the present invention, a similar additional gage arm 20 has been pivotally mounted on the machine frame to swing separately toward and from the path of the needle and concentrically with the channel guide gage 14. For this purpose the arm of the channel guide gage has an enlarged hub within which is rotatable the reduced hub portion of the gage arm 20, the gage arm 20 being pivotally mounted on an internally threaded stud 22 receiving within its threaded opening a clamp screw 24 for securing the stud to the frame of the machine. The needle gage arm 20 is formed at its outer end with a shoulder 26 extending laterally from the arm in such a position that it may engage the tip of the barb on the needle hook when the needle is at the limit of its work penetrating movement. To insure location of the needle actuating mechanism in a position corresponding to the extreme work penetrating position of the needle, it is necessary only to turn the sewing shaft of the machine manually until no further forward movement of the needle occurs.

To adjust the needle in its proper extreme work penetrating position by the use of the gage arm 20 the needle is released from its actuating mechanism, including a segment 28 by loosening a screw 30 which acts to clamp the shank of the needle between the segment and a cap plate 32 on the segment. The needle is then shifted in the segment until its hook engages the shoulder 26 on the gage arm 20 and the clamp screw 30 thereafter tightened to secure the needle in its adjusted position. After securing the needle in adjusted position the gage arm 20 may be swung downwardly to the position of Fig. 1 to prepare the machine for sewing operations.

With the use of the needle gage arm 20 and the channel guide gage 14 both the corresponding parts of the machine may be adjusted in correct relation for proper sewing operations. Thus, satisfactory sewing operations may be performed throughout the range of work types and qualities for which the machine is designed to operate correctly without the necessity of making further adjustments except to accommodate the originally gaged adjustments of the needle and channel guide. Once the machine has been set to sew satisfactorily with these two adjustments, further

changes are not needed for correct sewing operations under widely varying conditions.

The nature and scope of the invention having been indicated and a particular embodiment having been described, what is claimed is:

1. A shoe inseam sewing machine having stitch forming devices including a curved hook needle and a needle segment within which the needle is adjustably clamped, a channel guide, mechanism 10 for moving the guide toward and from the work having provision for adjustment to locate the lip of the channel guide transversely to the direction of feed and mechanism for actuating the needle segment to cause the needle to penetrate and retract 15 from the work, in combination with movable gage means arranged to be moved by the operator into a position to indicate the correct relation between the lip of the channel guide and the hook of the needle and to be moved away from said position 20 after the needle and channel guide have been adjusted.

2. A shoe inseam sewing machine having stitch forming devices including a curved hook needle and a needle segment within which the needle is 25 adjustably clamped, a channel guide, mechanism for moving the guide toward and from the work having provision for adjustment to locate the lip of the channel guide transversely to the direction of feed and mechanism for actuating the needle segment to cause the needle to penetrate and retract 30 from the work, in combination with movable gage means arranged to be moved by the operator into a position to indicate the correct relation between the lip of the channel guide and the hook 35 of the needle and to be moved away from said position after the needle and channel guide have been adjusted, comprising arms pivoted on the machine frame to swing separately toward and from gaging positions and provided with shoulders 40 for contacting the lip of the channel guide and the hook of the needle respectively.

3. A shoe inseam sewing machine having a main frame, stitch forming devices including a curved hook needle, a segment in which the needle is 45 adjustably clamped, and mechanism for actuating the segment to move the needle in an arcuate path toward and from the work, in combination with a movable gage arm having a lip pivoted on the machine frame to swing toward and from the 50 path of the needle to a position of contact between the lip and the hook of the needle when the needle is at the limit of its work penetrating movement.
